DEGASSER FOR INTERNAL-COMBUSTION ENGINES

Marion Mallory, Detroit, Mich.

Application October 26, 1945, Serial No. 624,750

10 Claims. (Cl. 123—97)

This invention relates to a degasser for an internal combustion engine.

It is the object of this invention to produce such a degasser which is of simple structure, efficient and reliable in operation and easily installed on the engine as original or accessory equipment. This object is accomplished by means of a throttle valve in the intake passageway on the engine side of the carburetor throttle valve which is automatically closed in response to intake passageway pressure whenever the carburetor throttle valve is closed and the engine is operating above a given speed. The closing of this valve causes substantially atmospheric pressure at the carburetor jets which stops the flow of fuel into the engine and at the same time admits air into the intake manifold between the engine and throttle valve to dilute any rich mixtures that might be trapped in the manifold on a sudden closing of the throttle valve, also reducing the vacuum over the pistons to reduce the drawing up of oil from the crank case into the combustion chamber.

Fig. 1 is a vertical section through my degasser assembled to the intake passageway.

Fig. 2 is a vertical section through a modified form of my degasser.

Fig. 3 is a section through a modified form of air bleed valve mechanism.

The elements shown in the drawings are referenced as follows: intake passageway 1, air inlet 2, fuel bowl 3, venturi 4, main fuel nozzle 5, idle jets 6, 7, throttle valve 8 of the butterfly type, valve shaft 9, crank 10 fixed on shaft 9, rod 11 by means of which throttle 8 is either manually or foot controlled, rod 13 pivotally connected at one end to crank 10 and carrying valve 14 at its other end, outlet 15 to the engine, passageway 16 connecting idle jets 6 and 7 into fuel pipe 17, throttle valve 18 of the butterfly type fixed on shaft 19, crank 20, rod 21 pivoted at one end to crank 20 and fixed at the other end to diaphragm 22 of suction device 23, conduit 24 connecting orifice 25 with orifice 26 in valve housing 27, conduit 28 connecting orifice 29 with suction chamber 30 of suction device 23, compression spring 31 tending to act through rod 21 to hold valve 18 open, valve 32 having circumferential groove 33, rod 34 connecting valve 32 with flexible diaphragm 35 in suction device 36, compression spring 37 tending to move valve 32 downwardly, conduit 38 connecting suction chamber 39 with air bleed port 40 and with conduit 41, conduit 42 communicating with conduit 41 and with orifice 43 on the engine side of valve 18, centrifugal valve

5 housing 44, stationary housing 45 open to atmosphere through port 46, valve shaft 47 which is driven off the engine so that it rotates in accordance with the speed of the engine, circumferential passageway 48, T passageway 4 in shaft 47 continuously communicating with passageway 48 and with valve cylinder 50, centrifugally unbalanced valve 51, air bleed port 52 controlled by valve 51, bypass passageway 53 permitting air to flow from port 52 to passageway 49 when valve 51 is open, tension spring 54 tending to hold valve 51 open.

The operation of my device is as follows: Throttle valve 18 is the conventional carburetor 15 butterfly throttle valve which, when in idle position, will permit sufficient charge to flow through the intake passageway to run the engine at idle speed. Throttle valve 18, however, is arranged so that when in closed position it will 20 substantially completely shut off intake passageway 1 so that no fuel charge can pass by valve 18. Spring 54 is tensioned so that valve 51 will close air bleed port 52 whenever the engine exceeds a predetermined speed, such, for example, 25 as 800 R. P. M. As shown in the drawings, throttle valve 8 is closed or in idle position and the engine is decelerating and running at a speed higher than, say, for example, about 800 R. P. M. In other words, the vehicle is overrunning the engine. At this time stopper valve 14 has air 30 speed 40 closed so that the intake passageway vacuum or suction at port 43 is established through conduits 42, 41 and 38 in suction chamber 39, thereby causing suction device or servo-motor 36 to raise valve 32 and place groove 33 in 35 registry with ports 29 and 26. This permits the intake passageway vacuum at port 25 to become established in suction chamber 30 which causes suction device 23, acting through rod 21 and crank 20, to draw valve 18 tightly closed. When 40 valve 18 closes completely, the pressure in intake passageway 1 on the atmosphere side of valve 18, or specifically at jets 5, 6 and 7, is atmospheric and therefore no fuel will be drawn from these 45 jets while the engine is decelerating.

In decelerating, as soon as the engine drops to a speed of, say, 800 R. P. M., at which valve 51 opens port 52, then air will be bled through port 52, passageways 53, 49, 48, 41, 38 into suction 50 chamber 39 to establish substantially atmospheric pressure in chamber 39 which causes spring 37 to lower piston valve 32 to thereby close port 26 and bring longitudinal groove 60 into communication with port 29 to bleed chamber 30 to atmosphere and thereby permit spring 31 to move 55

valve 18 wide open. When valve 18 opens, then intake manifold vacuum is established on the engine side of throttle valve 8 at port 7 and air is again drawn through inlet 2 to thereby draw fuel out of idle jet 7 sufficient to feed an idle charge to the engine. This will maintain the engine at idle speed.

When throttle valve 8 is open, then regardless of the engine speed, valve 14 will move clear of port 40 so that chamber 39 will bleed to atmosphere and valve 32 will be in lowered position to maintain groove 60 in communication with port 29 to thereby bleed port 30 to atmosphere and maintain valve 18 wide open.

In Fig. 1, the parts, such as valves 32, 51, 14 are all shown to be in a position when the vehicle is being decelerated above 800 R. P. M.

In the modified form shown in Fig. 2, the elements which differ from the elements shown in Fig. 1 are referenced as follows: unbalanced valve 61 for completely closing off intake passageway 1, crank 64 having extension 63, tension spring 65 tending to hold valve 61 open, piston valve 66 connected by rod 67 to flexible diaphragm 68, air bleed port 69 communicating by conduit 70 with port 71, port 72 on the engine side of valve 61 communicating with port 73 by conduit 74, circumferential passageway 75 in valve 66, rod 77 having abutment 78 arranged to contact extension 63 of crank 64, suction chamber 79 communicating by means of conduit 80 with conduit 81 and passageway 48, and port 82 in the intake passageway.

In Fig. 2, the parts are in a position when the vehicle is being decelerated above an engine speed of 800 R. P. M.

The operation of the modified form of my device is as follows: It is understood that valve 61 can be controlled by any conventional governor mechanisms such as the centrifugal weight type of governor or by the intake passageway suction as shown in my Patent 2,381,550. This invention can be used in conjunction with the different types of speed governors. Valve 61 would be the engine speed governor valve and my invention is simply applied to the engine speed governor. The important thing is that governor valve 61 is arranged so that, when the engine reaches its governed speed, valve 61 will move toward closed position to throttle the charge and maintain the engine at its governed speed in the manner of the conventional type governor. Assuming the engine was being decelerated from a speed above 800 R. P. M., throttle valve 8 would be closed, orifice 52 would be closed by piston valve 51 and conduit 40 would be closed. Suction then would establish in chamber 79 which would pull engine speed governor valve 61 absolutely closed and cause piston valve 66 to permit air to flow into the manifold through conduit 74. Even though the throttle 8 remained closed and orifice 40 remained closed, the carbureting system would go back to normal before the engine ever reached an idle speed because port 52 would be opened by piston 51 and this would bleed air into suction chamber 79. Under such conditions piston valve 66 would move to the left to release valve 61 and close conduit 74 and stalling of the engine is thereby prevented at idle or deceleration.

It is understood that my device can be used other than with a speed governor as shown in Figs. 1 and 2.

In the form of my invention shown in Fig. 1, I could use suction device 36 to directly open and

close valve 18 and thereby omit suction device 23 and intermediate valve mechanism 32. However, I prefer the arrangement shown in Fig. 1 because considerable power is required to close valve 18, especially if it is opposed by a governor spring such as 65 in Fig. 2, and in such case servo-motor 23 and its diaphragm 22 will be made considerably larger than servo-motor 36, which latter servo-motor simply serves as a remote controller for the larger servo-motor 23.

Instead of mechanically operating valve 14, I can operate this valve, as shown in Fig. 3, by means of the intake passageway suction. As shown in Fig. 3, valve 100 controls air bleed 49 and is mounted in valve housing 101 which communicates with intake passageway 1 on the engine side of valve 8 through port 102. Valve 100 is provided with a circumferential groove 103 which normally communicates with port 40 and conduit 38 due to the action of compression spring 104. In this form of the invention when throttle valve 8 is closed or in idle position, the suction at orifice 102 causes valve 100 to shift to the left and close off air bleed port 40. As soon as valve 8 is opened from idle position port 102 passes into the atmosphere and spring 104 moves valve 100 to the right and thereby places circumferential groove 103 in communication with port 40 and conduit 38 to admit atmosphere into chamber 39.

I claim:

1. In an internal combustion engine having an intake passageway and a throttle valve in said passageway, a vacuum operated fuel jet for delivering fuel into the intake passageway, a second throttle valve in said intake passageway on the engine side of said first mentioned throttle valve for shutting off the flow of motive fluid to said engine when closed, means actuated through changes of pressure in the intake passageway on the engine side of said second throttle valve for imparting movement to said second throttle valve, an air bleed to atmosphere for said pressure actuated means, means for closing said air bleed whenever the first mentioned throttle valve is in substantially closed position, and a speed controlled air bleed to atmosphere for said pressure actuated means arranged to close whenever the engine reaches a predetermined speed whereby when both of said air bleeds are closed said pressure actuated means moves said second throttle valve to closed position to thereby stop the flow of fuel from said jet into the intake passageway.

2. In an internal combustion engine having an intake passageway and a manually controlled throttle valve in said passageway, a vacuum operated fuel jet for delivering fuel into the intake passageway, a second throttle valve in said intake passageway on the engine side of said first mentioned throttle valve for shutting off the flow of motive fluid to said engine when closed, means actuated through changes of pressure in the intake passageway on the engine side of said second throttle valve for imparting movement to said second throttle valve, an air bleed to atmosphere for said pressure actuated means, means for closing said air bleed whenever the first mentioned throttle valve is in substantially closed position, a second air bleed to atmosphere for said pressure actuated means, and a speed controlled centrifugal valve arranged to close said second air bleed whenever the engine reaches a predetermined speed whereby when said manual throttle is closed and the engine is running above

said predetermined speed both of said air bleeds will be closed and said pressure actuated means will move said second throttle valve to closed position to thereby raise the pressure in the intake passageway on the atmosphere side of said second throttle valve to substantially atmospheric pressure and thereby stop the flow of fuel from said jet.

3. In an internal combustion engine having an intake passageway and a throttle valve in said passageway, a vacuum operated fuel jet for delivering fuel into the intake passageway, a second throttle valve in said intake passageway on the engine side of said first mentioned throttle valve for shutting off the flow of motive fluid to said engine when closed, means actuated through changes of pressure in the intake passageway on the engine side of said second throttle valve for imparting movement to said second throttle valve, an air bleed to atmosphere for said pressure actuated means, a valve for closing said air bleed, a connection between said air bleed valve and the first mentioned throttle valve whereby said air bleed valve is closed whenever the throttle valve is in idle position, and a speed controlled air bleed to atmosphere for said pressure actuated means arranged to close whenever the engine reaches a predetermined speed whereby when both of said air bleeds are closed said pressure actuated means moves said second throttle valve to closed position to thereby stop the flow of fuel from said jet into the intake passageway.

4. In an internal combustion engine having an intake passageway and a manually controlled throttle valve in said passageway, a vacuum operated fuel jet for delivering fuel into the intake passageway, a second throttle valve in said intake passageway on the engine side of said first mentioned throttle valve for shutting off the flow of motive fluid to said engine when closed, means actuated through changes of pressure in the intake passageway on the engine side of said second throttle valve for imparting movement to said second throttle valve, an air bleed to atmosphere for said pressure actuated means, a valve for closing said air bleed, a connection between said air bleed valve and the manual throttle valve whereby said air bleed is closed whenever the manual throttle valve is in idle position, a second air bleed to atmosphere for said pressure actuated means, and a speed controlled centrifugal valve arranged to close said second air bleed whenever the engine reaches a predetermined speed whereby when said manual throttle valve is closed and the engine is running above said predetermined speed both of said air bleeds will be closed and said pressure actuated means will move said second throttle valve to closed position to thereby raise the pressure in the intake passageway on the atmosphere side of said second throttle valve to substantially atmospheric pressure and thereby stop the flow of fuel from said jet.

5. The combination as set forth in claim 1 including a port in said intake passageway on the engine side of said second throttle valve for bleeding air into the intake passageway, and valve means controlled by said pressure actuated means for closing said air bleed port to the intake passageway whenever said second throttle valve is open and for opening said air bleed whenever said second throttle valve is closed.

6. In an internal combustion engine having an intake passageway and a throttle valve in said passageway, a vacuum operated fuel jet for deliv-

ering fuel into the intake passageway, a speed governor throttle valve in said intake passageway on the engine side of said first mentioned throttle valve adapted to move toward closed position whenever the engine reaches its governed speed, means actuated through changes of pressure in the intake passageway on the engine side of said governor throttle valve for imparting movement to said governor throttle valve, an air bleed to atmosphere for said pressure actuated means, means for closing said air bleed whenever the first mentioned throttle valve is in substantially closed position, and a speed controlled air bleed to atmosphere for said pressure actuated means arranged to close whenever the engine reaches a predetermined speed whereby when both of said air bleeds are closed said pressure actuated means moves said governor throttle valve to closed position to thereby stop the flow of fuel from said jet into the intake passageway.

7. In an internal combustion engine having an intake passageway and a manually controlled throttle valve in said passageway, a vacuum operated fuel jet for delivering fuel into the intake passageway, a speed controlled governor throttle valve in said passageway on the engine side of said manually controlled throttle valve and adapted to move toward closed position whenever the engine reaches its governed speed, means actuated through changes of pressure in the intake passageway on the engine side of said governor throttle valve for imparting movement to said governor throttle valve, an air bleed to atmosphere for said pressure actuated means, means for closing said air bleed whenever the first mentioned throttle valve is in substantially closed position, a second air bleed to atmosphere for said pressure actuated means, and a speed controlled centrifugal valve arranged to close said second air bleed whenever the engine reaches a predetermined speed whereby when said manual throttle valve is closed and the engine is running above said predetermined speed both of said air bleeds will be closed and said pressure actuated means will move said second throttle valve to closed position to thereby raise the pressure in the intake passageway on the atmosphere side of said second throttle valve to substantially atmospheric pressure and thereby stop the flow of fuel from said jet.

8. In an internal combustion engine having an intake passageway and a throttle valve in said passageway, a vacuum operated fuel jet for delivering fuel into the intake passageway, a speed controlled governor throttle valve in said intake passageway on the engine side of said first mentioned throttle valve and adapted to move toward closed position whenever the engine reaches its governed speed, means actuated through changes of pressure in the intake passageway on the engine side of said governor throttle valve for imparting movement to said governor throttle valve, an air bleed to atmosphere for said pressure actuated means, a valve for closing said air bleed, a connection between said air bleed valve and the first mentioned throttle valve whereby said air bleed valve is closed whenever the throttle valve is in idle position, and a speed controlled air bleed to atmosphere for said pressure actuated means arranged to close whenever the engine reaches a predetermined speed whereby when both of said air bleeds are closed said pressure actuated means moves said governor throttle valve to closed position to thereby stop

the flow of fuel from said jet into the intake passageway.

9. In an internal combustion engine having an intake passageway and a manually operated throttle valve in said passageway, a vacuum operated fuel jet for delivering fuel into the intake passageway, a speed controlled governor throttle valve in the intake passageway on the engine side of said first mentioned throttle valve and adapted to move toward closed position whenever the engine reaches its governed speed, means actuated through changes of pressure in the intake passageway on the engine side of said governor throttle valve for imparting movement to said governor throttle valve, an air bleed to atmosphere for said pressure actuated means, a valve for closing said air bleed, a connection between said air bleed valve and the manual throttle valve whereby said air bleed valve is closed whenever the manual throttle valve is in idle position, a second air bleed to atmosphere for said pressure actuated means, and a speed controlled centrifugal valve arranged to close said second air bleed whenever the engine reaches a predetermined speed whereby when said manual throttle valve is closed and the engine is running above said predetermined speed both of said air bleeds will be closed and said pressure actuated means will move said governor throttle valve to closed position to thereby raise the pressure in the intake passageway on the atmosphere side of said governor throttle valve to substantially atmospheric pressure and thereby stop the flow of fuel from said jet.

10. In an internal combustion engine having an intake passageway and a throttle valve in said passageway, a vacuum operated fuel jet for delivering fuel into the intake passageway, a second throttle valve in said intake passageway on the engine side of said first mentioned throttle valve for shutting off the flow of motive fluid to said engine when closed, means actuated through changes of pressure in the intake passageway on the engine side of said second throttle valve for imparting movement to said second throttle valve, an air bleed to atmosphere for said pressure actuated means, a valve for controlling said air bleed, a second means actuated through changes of pressure in the intake passageway on the engine side of said second throttle valve for imparting movement to said air bleed valve, an air bleed to atmosphere for said second pressure actuated means, means for closing said second air bleed whenever the first mentioned throttle valve is in substantially closed position, and a speed controlled air bleed to atmosphere for said second pressure actuated means arranged to close whenever the engine reaches a predetermined speed whereby when said second air bleed and speed controlled air bleed are closed said second pressure actuated means moves said first air bleed valve to closed position to thereby cause said first pressure actuated means to respond to intake passageway pressure and thereby close said second throttle valve which stops the flow of fuel from said jet into the intake passageway.

MARION MALLORY.
